M. A. WAGNER

UNDERCUTTING SAW REST

Original Filed May 2, 1923

INVENTOR.
M. A. WAGNER

BY *Victor J. Evans*
ATTORNEY.

UNITED STATES PATENT OFFICE.

MILTON A. WAGNER, OF GLENDALE, OREGON, ASSIGNOR OF ONE-HALF TO S. J. BASEEL.

UNDERCUTTING SAW REST.

Application filed May 2, 1923, Serial No. 636,160. Renewed December 15, 1924.

To all whom it may concern:

Be it known that I, MILTON A. WAGNER, a citizen of the United States, residing at Glendale, in the county of Douglas and 5 State of Oregon, have invented new and useful Improvements in Undercutting Saw Rests, of which the following is a specification.

This invention relates to new and useful 10 improvements in under-cutting saw rests.

The principal object of this invention is to provide a simple saw rest which may be attached to a support and one which may be readily moved to suit the convenience of the 15 user.

Another object is to provide a rest of this character which is simple in construction, and therefore cheap to manufacture.

A still further object is to provide a rest 20 which will enable one man to under-cut a log without undue effort upon the operator's part.

Other objects and advantages will be apparent during the course of the following 25 description.

In the accompanying drawings forming a part of this specification, and in which like numerals are employed to designate like parts throughout the same—

30 Figure 1 is a cross section taken on the line 1—1 of Figure 2,

Figure 2 is a side elevation of my device mounted upon a suitable support,

Figure 3 is a top plan view of Figure 1,

35 Figure 4 is a diagrammatic view showing the manner of using my device in connection with the sawing of a log, and

Figure 5 is an end elevation of a log 40 showing my device supporting a saw in under-cutting position.

It often happens that it is easier to saw a log by under-cutting than by sawing downwardly from the top as the natural weight of the log will cause the under-cut to spread and 45 not pinch the saw as is the case with the upper-cut which necessitates the use of wedges.

I have therefore designed a very simple 50 rest which may be attached to the handle of a woodsman's axe, which rest consists of a clamp having a roller pivotally mounted thereon, this roller having a groove within which the back of the saw is adapted to be moved.

55 In the accompanying drawings wherein

for the purpose of illustration is shown a preferred embodiment of my invention the numeral 5 designates a log, while the numeral 6 designates the head of an axe, while the numeral 7 refers to the straight handle of 60 the axe. It is obvious that other forms of axes may be used but I prefer the woodsman's axe having the straight handle.

At 8 I have shown a substantially semi-circular member to which is pivoted at 9 a 65 second semi-circular member 11. These two members form a clamp which is adapted to contact the handle 7 of the axe. Pivoted at 12 is a lever 13 having a link 14 secured thereto. The opposite end of this link is 70 adapted to be engaged in notches 16 formed in the free end of the semi-circular member 8.

Mounted upon the semi-circular member 8 is a yoke 17 within which a wheel 18 is 75 freely rotatable. This wheel 18 is grooved so as to receive the back of a saw 19.

The operation of my device is as follows:—

The axe is swung so that the head 6 is firmly embedded in the log to be sawed as 80 indicated in Figures 4 and 5. My clamp is then opened by swinging the parts to the position shown in dotted lines in Figure 1, and then placing the same around the handle 7 of the axe after which the clamp is ad- 85 justed as shown in full lines in Figure 1, after which the device is ready for use. The saw is now laid upon the roller so that the teeth of the same engage the under-side of the saw which is then reciprocated in the 90 usual manner.

It will thus be seen that I have provided a very simple yet efficient device which will 95 perform all of the objects set forth.

It is to be understood that the form of my 95 invention herewith shown and described is to be taken as a preferred example of the same, and that various changes in the shape, size and arrangement of parts may be resorted to without departing from the spirit 100 of the invention or the scope of the subjoined claim.

Having thus described my invention, I claim:—

In a device of the character described, a 105 substantially semi-circular member, a second substantially semi-circular member pivoted to said first member, a lever pivoted to the free end of said second mentioned member, a link pivoted to said lever, and adapted to 110

engage notches formed in the free end of said first mentioned semi-circular member in such a manner that said link will lie off center so as to cause said lever to contact the curved portion of said second mentioned semi-circular member, a yoke positioned on said first mentioned semi-circular member

and a roller freely rotatable in said yoke, substantially as and for the purpose specified.

In testimony whereof I affix my signature.

MILTON A. WAGNER.
